UNITED STATES PATENT OFFICE

ARTHUR W. FERRIN, OF KEYPORT, NEW JERSEY, ASSIGNOR, BY DIRECT AND MESNE ASSIGNMENTS, TO REMINGTON OIL ENGINE, INC., OF KEYPORT, NEW JERSEY, A CORPORATION OF NEW JERSEY

SAFETY CONTROL DEVICE FOR LIQUIDS

Application filed August 19, 1926. Serial No. 130,198.

This invention relates to liquid control devices in general and more particularly to control devices such as are used in conjunction with that type of heating apparatus commonly known as "oil burners."

6 An object of the invention is to provide a positive, safe, and highly efficient control device that is adapted to automatically regulate the flow of a liquid and to maintain its level at any predetermined height.

10 A further object of the invention is to provide a control device of the kind specified in which the regulation of the liquid is not entirely dependent upon a single control or 15 valve unit, and in which a high factor of safety is provided by the addition of an auxiliary shut-off valve unit adapted to function only when the primary or main control fails to operate from any cause.

20 A further and one of the principal objects of the invention is to provide a means especially suitable for the control of liquid fuels, in which the construction of the valves and another mechanism is such as to eliminate the 25 necessity of stuffing boxes or packing which frequently become leaky and which are therefore considered unsafe.

The present embodiment features a new and novel device in which the liquid ordinarily 30 passes directly into a main chamber, said liquid being maintained therein at a predetermined height by an adjustable settable means. Should said means fail to operate, however, for any reason, the improved 35 construction of the present invention will permit the liquid to overflow into an auxiliary chamber containing a safety valve mechanism operable by the rising liquid so as to positively interrupt the flow to the 40 main chamber until such a time as repairs have been made and the safety valve reset.

Further objects and advantages will be apparent from an inspection of the accompanying drawing which is a vertical section illustrating the invention in conjunction with an oil burner. The drawing discloses the preferred form of the invention which is shown 45 as a longitudinal section.

With reference to the drawing, 10 designates a form of burner or liquid fuel con-

sumer in which the surface area of the liquid fuel 11 may be increased or diminished in accordance with the height of the fuel maintained in the bowl 12. A supply pipe 13 connects the bowl 12 with the control device forming the present invention and which comprises a casing 14 preferably formed of a one-piece casting having an intervening wall 16 forming separate containers or chambers A and B which are connected by an opening 17 in the wall 16 at a height slightly below the highest level the liquid should reach in the bowl 12.

55 The chamber A is provided with a flexible member 18 preferably comprising a metallic bellows diaphragm of a type well known in the art, the bottom of which is held in a fixed position by a screw plug 19 provided with a suitable opening 20 connecting with the interior of the diaphragm.

60 Secured to the top or movable portion of the diaphragm is a float mechanism 21 comprising a float 22, a needle valve 23 operable by said float, and a needle valve seat portion 24 secured to the top of the diaphragm and 65 provided with a plurality of openings 25 forming an exit for the fluid 11 subject to the action of said needle valve. A screw 26 with its associated hand wheel 27 controls the raising or lowering of the float actuating 70 means to any desired setting and the needle valve and its seat and the float will simultaneously move up or down therewith due to the flexibility of the diaphragm 18.

75 In the chamber B there is a similar but somewhat smaller flexible member or diaphragm 29 also having its lower portion held in fixed relation with the casing 14, said diaphragm having an opening through its bottom connecting with a lower chamber C 80 through which passes the stem 30 of a taper seated safety valve 31, and a suitable conduit 32 connects said opening with the opening 20.

85 A spring 33 tending to close the valve 31 is mounted on the stem 30 and a latch 34 is provided to normally keep the valve in an open position, said latch being releasable by a float 35. A drain plug 36 permits of the liquid 90 being drawn from the chamber B, and a man-

ually operable lever 37 forms the means for setting or resetting the device to a normally open position of the valve 31. It might be said in passing, that the top of the diaphragm 29 should be made air tight and this can be readily accomplished in any convenient manner, as the valve stem 30 which passes therethrough moves up or down only with the top of the diaphragm and has no movement relatively thereto.

The mechanism operates in the following manner. From a main supply tank (not shown) the liquid is conducted by means of a supply line 38 to the lower chamber C, passing through a screen 39, thence being conducted by means of the normally open valve 31, conduit 32, and opening 20 to the interior of the diaphragm 18 from whence it issues by means of the openings 25, into the chamber A from which it is conveyed to the bowl 12 by the pipe 13. Should the float 22 and its associated needle valve fail for any reason to stop the influx of the fuel when the high level is reached, the liquid will overflow into the chamber B by means of the opening 17 and thus prevent an overflow in the burner bowl 12. Should this overflow continue until sufficient liquid has found its way into this chamber to operate the float 35 it will release the latch 34 and permit the spring to close the valve 31 and shut off the liquid until such a time when the device is manually reset by the lever 37 following such repairs as may have been found necessary.

Special attention is directed to the fact that with the construction as herein shown and described, the operation of the valve 31 is not solely dependent upon the spring 33, and it will be understood that the expansive characteristics of a compressed diaphragm is such that it will in itself cause the valve to close. Also that the pressure of the liquid from within the diaphragm will be sufficient to distend the same and close the valve in the event of the other means failing.

Attention is further directed to the fact that with the embodiment as herein disclosed, all non-metallic material such as packings have been avoided and that a leak-proof device which will assure the highest efficiency has been provided.

In its specific application the present invention has been shown in conjunction with an oil burner for sake of illustration. It is obvious however, that the device is adapted for general application wherever a liquid control means is a requisite.

Although one specific embodiment of the invention has been particularly shown and described, it will be understood that the invention is capable of modification and that changes in the construction and in the arrangement of the various cooperating parts may be made without departing from the

spirit or scope of the invention as expressed in the following claims.

Having thus described my invention, I claim:

1. A float chamber device comprising a casing providing a reservoir, inlet and outlet conduits, a valve between the inlet conduit and the reservoir for controlling the flow of liquid to said reservoir, a float for operating said valve, a chamber within said casing free from the liquid during the normal operation of the float chamber device, a passage connecting said reservoir and said chamber so that liquid may flow into said chamber when said valve accidentally remains open, and means controlled by the level of the liquid in said chamber for controlling the flow of liquid through said inlet conduit, said means being located between said valve and the source of supply.

2. A liquid control unit comprising a casing having a partition providing a reservoir and a chamber, inlet and outlet conduits connecting the reservoir, a valve between the inlet conduit and reservoir for controlling the flow of liquid to said reservoir, a float for operating said valve, a passage through the partition whereby liquid may flow from the reservoir to the chamber when the level thereof in the reservoir reaches a given height, and means in said chamber controlled by the level of liquid for closing said inlet conduit.

3. In apparatus of the class described, the combination of, a control unit having two chambers, means in one of said chambers adapted to maintain a predetermined level of liquid therein, a conduit connecting said chamber with a source of supply, a normally open valve in said conduit, and a valve control mechanism including a flexible diaphragm adapted to actuate said valve; said mechanism being disposed in a second chamber and responsive to an overflow of the liquid from the first chamber into the second chamber beyond a predetermined point to effect a closure of the valve.

4. In apparatus of the class described, the combination of a control unit having two chambers, adjustable control means for the inflow of liquid into said unit, including a flexible diaphragm in one of said chambers; said diaphragm adapted to permit variation in the adjustment of the control means so as to maintain a predetermined level of liquid in said chamber, a conduit connecting said chamber with a source of supply, a normally open valve in said conduit, and a valve control mechanism in a second chamber, said mechanism being responsive to an overflow of liquid from the first chamber into the second chamber to effect a closure of the valve.

5. In apparatus of the class described, the combination of a casing having two chambers, liquid level control mechanism in one of said chambers comprising a flexible member and a

- float mechanism including a valve unit consisting of a float, float valve and valve seat secured to the upper portion of the flexible member and vertically adjustable with the same, a supply line for the liquid, a normally open valve in said supply line, a valve operating mechanism contained in another chamber and comprising a normally compressed flexible member having connection with said normally open valve, means tending to distend the flexible member and close the valve, a latch adapted to maintain both said flexible member and valve in their normal open position, and a float operative to 10 engage said latch; said float being responsive to an overflow of the fuel from the first chamber into the second chamber.
6. A liquid control mechanism comprising a unit having a chamber, a hollow flexible member within the chamber having its lower portion secured thereto, a valve having a seat secured to an upper vertically movable portion of the flexible member, float mechanism also secured to the upper portion of the flexible member and manually adjustable to various heights, and means to permit the liquid to pass into said flexible member and by said valve subject to the action of said float mechanism.
- 30 7. A liquid control mechanism comprising a unit having a chamber, a supply line, a normally open valve in said line, a flexible member in said chamber having its lower portion in fixed relation therewith and an upper vertically movable portion connecting with the valve, spring means tending to close the valve, a latch adapted in its engaged position to maintain the valve in an open condition, and a float operable by a rising fluid to disengage the latch.
8. In apparatus of the class described the combination of a unit having a chamber, a liquid conducting line connecting with said chamber, a control mechanism including a float and valve vertically adjustable within the chamber and adapted to maintain a predetermined level of liquid therein, a normally inactive auxiliary control mechanism including a normally open valve in the conducting line and means responsive to an excessive amount of liquid in said chamber to close said normally open valve.
9. In apparatus of the class described, the combination with a unit having a chamber and a mechanism adapted to confine a fluid to a predetermined height therein and a supply line therefor, of a normally inactive safety control mechanism comprising a normally open valve in said supply line, means associated with said unit including a flexible member tending to close said valve, a latch to maintain the valve in its open position, and a float adapted to release said latch; the float being responsive to the fluid only when the same exceeds said predetermined amount in said chamber.
10. In apparatus of the class described, the combination with a liquid fuel consumer, of a control means between said consumer and a source of supply, comprising a casing divided into a plurality of chambers, means to permit an overflow of liquid from one chamber to another, a supply line connecting said consumer with the first chamber, a liquid control mechanism in said first chamber comprising a hollow flexible member having a vertically adjustable upper portion provided with an opening and a fixed lower portion also provided with an opening, a float mechanism secured to said upper movable portion of the flexible member, comprising a valve adapted to close said upper opening, a safety control mechanism contained in the second chamber comprising a hollow flexible member having a vertically movable closed upper portion and a fixed lower portion provided with an opening, a supply line having a connection with the lower opening of the flexible member in said first chamber and a source of supply, a valve having a stem connected to said upper portion of the flexible member in said second chamber and movable through said opening in the lower portion; said valve adapted to form a closure for the last said supply line, a spring tending to close said valve, a latch adapted to normally maintain said valve in an open condition, and a float means responsive to the overflow of the liquid from the first into the second chamber to release the latch so as to permit the valve to close.
11. In apparatus of the class described, the combination of a fuel control unit comprising two chambers, a conduit connecting with one chamber, a control mechanism in said chamber adapted to maintain a predetermined level of liquid therein and including a float, a valve seat and a valve vertically adjustable as a unit within the chamber and operable at various heights, a normally open valve in said conduit, and a means within the second chamber adapted to close said valve; said means being responsive to an overflow of liquid from the first chamber into the second chamber.
12. In a safety control device for liquids, the combination of a control unit having a chamber, a conduit having connection with said chamber, adjustable means within said chamber adapted to control the flow of liquid through said conduit into said chamber and to maintain the liquid under normal conditions at a predetermined height therein, a second chamber, a means adapted to permit a flow of liquid from the first chamber into the second chamber when said liquid rises beyond the predetermined height in the first chamber, a normally open valve in said conduit, a means in the second chamber having

connection with said valve and responsive to the rising of the liquid within the second chamber so as to close said valve and positively interrupt the flow of liquid into the 5 first chamber.

13. In an apparatus adapted to maintain a predetermined level of liquid in a liquid consumer, the combination with a chamber having a liquid supply line, of a flexible 10 member in said chamber, a valve seat secured to said flexible member and adjustable therewith, a valve in said chamber adapted to co-act with said seat, and a float actuated by the liquid to control the valve.
14. In apparatus adapted to maintain a predetermined level of liquid in a liquid consumer, the combination with a chamber having a conduit, a flexible member in said chamber, a valve seat secured to said flexible 15 member and adjustable therewith, a valve to co-act with said seat, a float to control the valve so as to close communication between said conduit and said chamber when the liquid rises to a predetermined level, a supply 20 line connecting said conduit with a source of supply, a normally open valve in said conduit, a flexible member connected to the last said valve and adapted to close the same, a latch adapted to maintain the normally open 25 30 position of the valve, a second chamber, and a float in said chamber responsive to the liquid when it rises beyond said predetermined level in the first chamber and adapted to release the latch.
- 35 Signed at Keyport, in the county of Monmouth, and State of New Jersey this 17th day of August A. D. 1926.

ARTHUR W. FERRIN.
